[57] CLAIM

The ornamental design for a color transparency reader, as shown and described.

DESCRIPTION

FIG. 1 is a perspective view of the top, front and right side of a color transparency reader showing our new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof;

FIG. 7 is a bottom plan view thereof; and,

FIG. 8 is a perspective view thereof, the broken line showing of a machine is for illustrative purposes only and forms no part of the claimed design.
